J. S. HOPE

TOY

Filed Oct. 8, 1923

James Shirley Hope
Inventor

By *Ogle R. Singleton.*
Attorney

UNITED STATES PATENT OFFICE.

JAMES SHIRLEY HOPE, OF PORTSMOUTH, VIRGINIA.

TOY.

Application filed October 8, 1923. Serial No. 667,266.

To all whom it may concern:

Be it known that I, JAMES SHIRLEY HOPE, a citizen of the United States, residing in the city of Portsmouth, in the county of 5 Norfolk and State of Virginia, have invented certain new and useful Improvements in Toys, of which the following is a specification.

My invention consists in a new and useful 10 improvement in toys and is designed to provide an improved figure wheeled toy in which the parts are so related that when the toy is rolled a movable element is caused to reciprocate. The particularly novel feature 15 of my device is the relation between the wheels or rollers upon which the toy is mounted and the movable element. The movable element is pivotally mounted in the body of the toy and the wheels are 20 provided with a crank arm which, as it rotates, causes pressure upon a flexible cord, one end of which is fastened to the body of the toy and the other end to the movable element.

25 While I have illustrated in the drawings filed herewith a specific embodiment of my invention, it is to be distinctly understood that I do not consider my invention limited to the details of construction therein dis-

30 closed but refer for its scope to the claim appended hereto.

In the drawings:

Fig. 1 is a side elevation of my improved toy.

35 Fig. 2 is a front elevation.

My toy is composed of the body portion 1 to which are attached the front axle 2 and the rear axle 3. The body is provided with a recess 4 near its upper edge and a channel 5 leading from the recess 4 to and through the front axle 2 which is provided at its portion directly under the body 1 with a recess 6. Rotatably mounted on the underside of the front axle 2 in the staples 7, there 40 is the operating axle 8 provided with the crank arm 9 and the fixed attached wheels 10. Wheels 11 are rotatably mounted upon the ends of the rear axle 3.

I provide a movable element 12 with a 45 tongue 13 which is inserted into the recess 4 and is pivotally mounted in the body 1 by

the pin 14. The inner end 15 of the tongue 13 is disposed within the recess 4 directly above the channel 5. The element 12 is so pivoted that its center of gravity is forward 55 of the pivot pin 14 causing the portion outside of the body 1 normally to drop forwardly and the tongue 13 to extend upwardly within the recess 4. An operating cord 16 has its upper end attached to the 60 inner end 15 of the tongue 13, passes downwardly through the channel 5, about the crank arm 9 of the axle 8 and has its lower end attached to the projection 17 of the body 1 adjacent the axle 2. The parts are so proportioned and related that when the crank arm 9 is in the position indicated in Fig. 2, the cord 16 is slack and the movable element 12 is permitted to rest in normal position. When the toy is pulled or pushed 65 either forward or backward, the rotation of the wheels 10 causes the rotation of the crank arm 9 and as the crank arm 9 moves from its perpendicular position indicated in Fig. 2 it presses against the operating cord 16 and since the lower end of the cord 16 is fastened to a fixed point the pressure causes the cord 16 to draw the tongue 13 downwardly, causing the movable element 12 outside of the body 1 to rise. 70 When the crank arm 9 moves into a position to release the pressure upon the cord 16, the movable element assumes its normal position by the action of gravity. Thus it will be obvious that the travel of the toy automatically causes the reciprocation of the 75 movable element 12.

Having described my invention, what I claim is:

In a toy, the combination of a body portion; a movable element pivotally mounted in said body portion; wheels rotatably mounted on said body portion; a crank arm adapted to be rotated by said wheels; an operating cord having one end fastened to 90 said body portion and the other end fastened to said movable element, said cord being disposed in the path of rotation of said 95 crank arm.

In testimony whereof I affix my signature.

JAMES SHIRLEY HOPE.
